DESIGN FOR A DRIP COFFEEPOT

Richard F. Krause, Massillon, Ohio

Application November 30, 1934, Serial No. 54,206

Term of patent 14 years

To all whom it may concern:

Be it known that I, Richard F. Krause, a citizen of the United States, residing at Massillon, in the county of Stark and State of Ohio, have invented a new, original, and ornamental Design for a Drip Coffeepot, of which the following is a specification, reference being had to the accompanying drawing, forming part thereof.

Figure 1 is a side elevation of a drip coffeepot, showing my new design;

Fig. 2, a top plan view of the drip coffeepot shown in Fig. 1; and

Fig. 3, a fragmentary section through the lid and upper portion of the drip coffeepot taken on the line 3—3, Fig. 2.

I claim:

The ornamental design for a drip coffeepot, as shown.

RICHARD F. KRAUSE.
